(57) **CLAIM**

I claim the ornamental design for an image magnifying and polarizing lens assembly for measuring device, as shown and described.

DESCRIPTION

FIG. 1 is a perspective view of an image magnifying and polarizing lens assembly for measuring device, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings show portions of the image magnifying and polarizing lens assembly for measuring device that form no part of the claimed design.
